UNITED STATES PATENT OFFICE.

FRANK J. HERRICK, OF NEW BRITAIN, CONNECTICUT.

DESIGN FOR A BELT-CLASP.

SPECIFICATION forming part of Design No. 19,579, dated January 14, 1890.

Application filed December 20, 1889. Serial No. 334,444. Term of patent 7 years.

To all whom it may concern:

Be it known that I, FRANK J. HERRICK, a citizen of the United States, residing at New Britain, in the county of Hartford and State 5 of Connecticut, have invented and produced a new and original Design for Belt-Clasps, of which the following is a specification, reference being had to the accompanying drawings, forming a part thereof.

10 Figure 1 is a front view of a belt-clasp showing my design. Fig. 2 is a detail edge view of the same.

The leading feature of my design consists in an oblong loop *a*, of metal, with a central 15 bar *b* extending lengthwise of the loop. The front surface of the loop has a chain of cup-

like depressions *c*, bounded by a rim, the surface of the material sloping downward and outward from the edge or rim and curving, so as to give a scalloped appearance to the 20 bounding edges *d* at the sides of the loop.

I claim as my invention—

The design for a belt-clasp, substantially as herein shown and described, the same comprising a metallic loop having its surface 25 shaped to form a series of cup-like depressions with scalloped bounding edges, all substantially as described.

FRANK J. HERRICK.
